SAXOPHONE

Floyd E. Comer, Elkhart, Ind., assignor to
 Buescher Band Instrument Company, Elkhart,
 Ind.

Application August 16, 1939, Serial No. 290,469

9 Claims. (Cl. 84—385)

This invention relates to musical instruments and more particularly to improvements in saxophones.

An object of this invention is to provide a 5 saxophone wherein the valves in the lower register are so positioned that they will not contact with the clothes of the player.

Another object of this invention is to provide an instrument of this kind wherein an improved 10 operating means is provided for the valves in the lower register.

A further object of this invention is to provide an instrument of this kind wherein the placement of the valves in the lower register will eliminate the necessity of clothing guards, thus reducing the weight of the instrument.

A still further object of this invention aims to provide a saxophone wherein the valves in the lower register can be readily operated by pressure 20 of a little finger and wherein the lower valves are connected to the operating keys through a linkage rather than through a direct connection as is at present the case.

Embodying the aims aforesaid and others 25 which may hereinafter appear, the invention consists of the novel construction, combination and arrangement of parts to be more specifically described and as illustrated in the accompanying drawing, wherein is shown an embodiment of the 30 invention, but it is to be understood that changes, variations and modifications may be resorted to which fall within the scope of the invention as claimed.

Figure 1 is a detailed side elevation of a saxophone constructed according to an embodiment 35 of this invention, certain of the keys and valves being removed.

Figure 2 is an enlarged fragmentary side elevation of the lower portion of the saxophone,

Figure 3 is a sectional view taken on the line 40 3—3 of Figure 2, and

Figure 4 is a sectional view taken on the line 4—4 of Figure 3.

Referring to the drawing, the numeral 10 designates a mouth pipe having a mouth piece 11 on 45 the upper end thereof. A downwardly tapering tone pipe 12 is detachably secured at its upper end to the lower or down turned end of the mouth pipe 10 and a U-shaped bow pipe 14 is secured on one leg thereof to the lower or large 50 end of the tone pipe 12. The tone pipe 12 on the inner side thereof and adjacent the lower end is provided with a finger grip 13 and the opposite leg 15 of the bow pipe 14 has a bell 16 secured thereto. The outer leg 15 of the bow pipe 14

is substantially shorter in length than the inner leg 17.

At the present time in our construction of saxophones the last three or four valves in the lower register are positioned on the bow pipe 14 and the bell 16 with certain of the valves on the bell 16 positioned on the side of the bell opposite from the remaining valve or valves. In addition to this at the present time, one of the lower valves is positioned on the rear side of the bow so that 10 it is necessary to mount a clothing guard on the lower rear valve and the two valves which are mounted on the bell on the side thereof opposite from the third-most lower valve. It is necessary to provide guards to keep the valves from being 15 fouled by clothing of the player and also to protect these pads or valves. If the instrument were not provided with guards, it is very likely that these keys would be knocked out of line when, for instance, the player laid the instrument on a 20 table. The slightest jar is likely to bend the keys, and if they are bent, they do not fit properly on the socket, hence they leak.

In the structure shown in Figure 1, the valves in the upper registers have for the most part been 25 omitted, but it will be understood that the saxophone disclosed in Figure 1 will be provided with the usual or normal number of valves and operating keys therefor. The bell 16 adjacent the upper end thereof and on the inner side is connected to the tone pipe 12 by means of a connecting or bracing bar 18, which has an angularly disposed outer end portion 19 secured to a reinforcing plate 20 which is fastened as by solder or the like to the inner side of the bell 16. 30

The bell 16 is provided adjacent the lower end thereof and on the inner sector with a pair of outstanding cylindrical valve seats 21 and 22. The instrument herein disclosed is an E-flat saxophone and the valve seat 21 is the lowermost or 40 B-flat valve seat, whereas the valve seat 22 is the B valve seat. The outer leg 15 of the bow pipe 14 is provided on an inner sector thereof with a valve seat 23, which is positioned in vertical alignment with the valve seats 21 and 22. The 45 bight of the bow pipe 14 is provided in a side thereof with an outstanding valve seat 24 and a valve member (not shown) is adapted to engage the seat 24. The valve seat 23 is the C-sharp valve seat, whereas the valve seat 24 is the C 50 valve seat. The inner leg 17 of the bow member 14 is provided on an inner sector thereof with a valve seat 25, which is positioned adjacent the upper end of the inner leg 15. A valve member 26 provided with a pad 27 is adapted to engage 55

the valve seat 21 and has an arm 28 secured thereto. The arm 28 is fixed to a shaft 29, which is mounted between a pair of upstanding bearing posts 30 and 31. Preferably the shaft 28 is of hollow construction and an inner stationary pin is disposed between the two posts 30 and 31.

A lever or link 32 is fixed to the tubular shaft 29 at one side of the lever 28 and extends at a substantially acute angle to the lever 28 projecting in the direction of the tone pipe 12. The inner or rear end of the link 32 has removably mounted thereon a pin 33 having a cushion 34 in the form of a yieldable sleeve disposed thereabout. The pin 33 is preferably a threaded pin 15 provided with a slotted head so that the pin 33 may be removably secured in the inner or free end of the link 32. A tubular shaft 35 is mounted between a pair of outstanding bearings 36 and 37, which are fixed to the tone pipe 12. A link 20 38 is fixed to the tubular shaft 35 and projects in the direction of the link 32 with the outer or free end thereof overlapping the inner free end of the link 32. The free end of the link 38 is provided with an elongated slot 39 opening 25 through the outer or free end of the link 38 and the cushioned pin 33 is adapted to slidably engage in the slot 39. The valve member 26 is normally biased to an opened position by conventional spring devices (not shown).

30 A valve member 40 provided with a pad or gasket 41 is adapted to engage on the valve seat 22 and has an arm or a lever 42 secured thereto. The arm 42 is fixed to a tubular shaft 43 disposed in axial alignment with the tubular shaft 29 and rockably mounted on the same pin as the shaft 29. A link 44 is fixed to the tubular shaft 43 and is disposed at an acute angle to the lever or arm 42, as shown in Figure 3. The construction of the arm 42 and the relation of this 35 arm 42 to the link 44 is the same as the arm or lever 28 and the link 32. A tubular shaft 45 is disposed in axial alignment with the tubular shaft 35 and a link 46 is fixed to the tubular shaft 45 and projects outwardly in the direction 40 of the link 44 with the outer free end thereof disposed in overlapping relation with respect to the link 44. The link 46 is provided in its outer end with a slot 47 within which a pin 48 slidably engages. The pin 48 is threaded into the link 50 46, as shown in Figure 4 and is provided with a head 49 engaging against the outer end of a cushioning sleeve 50. The sleeve 50 is slidable between the bifurcations of the arm or link 46. An arm or stop member 51 is fixed to the tubular shaft 45 and is adapted to engage the periphery of the tone pipe 12 so as to limit the opening of the valve member 40. The free end of the arm 51, which engages the surface of the tone pipe 12 is adapted to have a cushioning means secured 55 thereto.

60 A valve member 52 is adapted to engage the seat 23 and is provided with a pad or sealing member 53. The valve member 52 is secured to a lever 54, which is fixed to a tubular shaft 55. The shaft 55 is rockably mounted between a lower bearing 57 and a bearing 56. The tubular shaft 55 has fixed thereto a pair of spaced apart ears or arms 58 and a tubular shaft 59 is rockably mounted between the two arms or ears 58. A link 59 is fixed at one end to the tubular shaft 58 and at the opposite end to a tubular shaft 60. The shaft 60 is disposed between a pair of arms 61, which are fixed to an elongated tubular shaft 62 which is rockably mounted between a pair 70 75 of bearings 63 and 64. An operating key 65 is

secured in laterally disposed relation to the upper end of the tubular shaft 62. The valve member 54 is normally biased to a closed position whereas the two valve members 26 and 40 are normally biased to an open position.

5 The tubular sleeve 35 associated with the valve 26 has an operating key 66 secured to the upper end thereof and the tubular sleeve or shaft 45 has an operating key 67 secured thereto through a connecting bar 68 and a link 69. A valve member 70 10 is associated with the valve seat 25 and has an arm or lever 71 fixed thereto. The arm or lever 71 is fixed to a tubular shaft 72 mounted between a pair of outstanding bearings 73. An operating key 74 is fixed to a lever 75, which is 15 fast on a tubular shaft 76 mounted between a pair of bearings 77. A lever 78 of substantially L-shape has one leg thereof secured to the tubular shaft 72 and the opposite leg thereof is free and is disposed beneath the operating key 74. A stop 20 arm 79 is fixed to the tubular shaft 76 and is adapted to engage the periphery of the tone pipe 12, being provided on its contacting end with a cushioning means.

25 The operation or playing of the instrument hereinbefore described is the same as a conventional instrument, the operating keys being disposed in the same relative positions with respect to the tone pipe 12 as is the case with conventional instruments. It will be noted, however, that 30 on the rear or inner side of the tone pipe 12 and the inner leg 15 of the bow pipe 14 that there are not valves, guards or mountings which are apt to catch on the clothing of the player. By positioning the valve members 26, 40 and 52 on the 35 inner sector of the bell 16 and the bow pipe member 15, it is not necessary to provide clothing guards for the valve members, thus eliminating a considerable amount of weight. Through the use of the sliding connection between the operators 40 for the two valves 26 and 40 these valves may be readily biased to an open position and these valves may be positioned at any suitable point on the inner sector of the bell 16. In the present instance, the valves 26 and 40 are positioned in 45 confronting relation to the lowermost valves carried by the tone pipe and which are associated with valve seats 89 and 81 fixed to the lower portion of the tone pipe 12 on the outer sector thereof.

50 The valve seats 21, 22 and 23 are disposed in such a position that when the valves 26, 40 and 52, respectively, are moved to an open position the movement of these valves will be a rearward and inward movement toward the tone pipe 12 and the rear leg of the bow pipe 14. In this manner when the instrument is in use the valves 26, 55 40 and 52 will not be swung outwardly and laterally as is the case where the valve seats and valves are positioned on the side of the bell and bow pipe.

60 It is to be understood that while the instrument here shown constructed according to this invention is an E-flat alto saxophone, the invention may also be used with B-flat tenor saxophones, E-flat baritone saxophones, E-flat bass saxophones and B-flat curved soprano saxophones.

65 What I claim is:

1. In a saxophone including a tone pipe and a bell, a plurality of vertically spaced apart valve seats on said bell on an inner sector of the rear 70 one-half thereof, said seats being disposed in alignment, a valve for each seat, and operating means for said valves, said operating means moving said valves rearwardly and inwardly to an open position.

2. In a saxophone including a tone pipe, a U-shaped bow pipe and a bell, a plurality of vertically spaced apart valve seats on an inner sector of the rear one-half of said bell, said seats being disposed in alignment, a valve for each seat, a shaft for each valve, means pivotally mounting said shafts on said bell on an inner sector of the rear one-half thereof, an arm secured to each shaft and a valve, a lever fixed to each shaft projecting in the direction of said tone pipe, a right angularly disposed pin carried by each lever, an operating shaft for each lever, means pivotally mounting said operating shafts on said tone pipe, a key for each operating shaft, and a lever fixed to each operating shaft, said latter levers having a slotted end engaging a pin of said first levers, said operating means moving said valves rearwardly and inwardly to an open position.
3. In a saxophone including a tone pipe, a U-shaped bow pipe and a bell, a lower valve seat carried by said bow pipe on the outer leg thereof and on an inner sector of the rear one-half of said outer leg, a plurality of valve seats on said bell in alignment with said first valve seat and disposed on an inner sector of the rear one-half of said bell, a valve for each valve seat, and operating means for said valves, said operating means moving said valves rearwardly and inwardly to an open position.
4. In a saxophone including a tone pipe, a U-shaped bow pipe and a bell, a lower valve seat carried by said bow pipe on the outer leg thereof and on an inner sector of the rear one-half of said outer leg, a plurality of valve seats on said bell in alignment with said first valve seat and disposed on an inner sector of the rear one-half of said bell, a valve for each valve seat, and operating means for said valves, said operating means including a link fixed relative to a valve, a second link, means pivotally mounting said second link on said tone pipe, and a loose connection between said links, said operating means moving said valves rearwardly and inwardly to an open position.
5. In a saxophone including a tone pipe, a U-shaped bow pipe and a bell, a lower valve seat carried by said bow pipe on the outer leg thereof and on an inner sector of the rear one-half of said outer leg, a plurality of valve seats on said bell in alignment with said first valve seat and disposed on an inner sector of the rear one-half of said bell, a valve for each valve seat, operating means for said valves, said operating means including a link fixed relative to a valve, an operating shaft, for each valve, means pivotally mounting said shafts on said tone pipe, a link fixed to each shaft and having the free end thereof overlapping an adjacent end of a valve link, and a sliding connection between the overlapping ends of said links said operating means moving said valves rearwardly and inwardly to an open position.
6. In a saxophone including a tone pipe, a U-shaped bow pipe and a bell, a lower valve seat carried by said bow pipe on the outer leg thereof and on an inner sector of the rear one-half of said outer leg, a plurality of valve seats on said bell in alignment with said first valve seat and disposed on an inner sector of the rear one-half of said bell, a valve for each valve seat, operating means for said valves, said operating means including a link fixed relative to a valve, an operating shaft for each valve, means pivotally mounting said shafts on said tone pipe, a link fixed to each shaft and having the free end thereof overlapping an adjacent end of a valve link, the free end of one link having an elongated slot therein, and a pin carried by the overlapping end of an adjacent link slidably engaging in said slot said operating means moving said valves rearwardly and inwardly to an open position.
7. In a saxophone including a tone pipe, a U-shaped bow pipe and a bell, a lower valve seat carried by said bow pipe on the outer leg thereof and on an inner sector of the rear one-half of said outer leg, a plurality of valve seats on said bell in alignment with said first valve seat and disposed on an inner sector of the rear one-half of said bell, a valve for each valve seat, operating means for said valves, said operating means including a link fixed relative to a valve, an operating shaft for each valve, means pivotally mounting said shafts on said tone pipe, a link fixed to each shaft and having the free end thereof overlapping an adjacent end of a valve link, the free end of one link having an elongated slot therein, a pin carried by the overlapping end of an adjacent link slidably engaging in said slot, and a cushioning sleeve carried by said pin said operating means moving said valves rearwardly and inwardly to an open position.
8. In a saxophone including a tone pipe and a bell, a plurality of vertically spaced apart valve seats on said bell, said seats being disposed in alignment and on the inner or rear half of the bell within a range of forty-five degrees of the center of the rear half of the bell, a valve for each seat, and operating means for said valves the movement of a valve to an open position being a rearward and inward movement in the direction of the tone pipe.
9. In a saxophone including a tone pipe, a U-shaped bow pipe and a bell, a lower valve seat carried by said bow pipe on the outer leg thereof and on an inner sector of the rear one-half of said outer leg, a second valve seat carried by said bow pipe on the inner leg thereof and on an outer sector of said inner leg, a plurality of valve seats on said bell in alignment with said first valve seat and disposed on an inner sector of said bell, a valve for each valve seat and operating means for said valves said operating means moving the valves engaging the seats on said bell rearwardly and inwardly to an open position.

FLOYD E. COMER.
